CLAIM

The ornamental design for a styling comb, as shown and described.

DESCRIPTION

FIG. 1 is a top, front and right-side perspective view of a styling comb, showing my new design;

FIG. 2 is a top, rear and left-side perspective view thereof;

FIG. 3 is a front elevation view thereof;

FIG. 4 is a rear elevation view thereof;

FIG. 5 is an enlarged portion of the front elevation view thereof;

FIG. 6 is an enlarged portion of the rear elevational view thereof;

FIG. 7 is a left-side elevation view thereof;

FIG. 8 is a right-side elevation view thereof;

FIG. 9 is a top plan view thereof;

FIG. 10 is a bottom plan view thereof; and,

FIG. 11 is an enlarged portion of the bottom plan view thereof.
